UNITED STATES PATENT OFFICE

2,086,074

EJECTOR HEAD OF BURNERS, ATOMIZERS,
AND SIMILAR NOZZLES

Pietro Del Genovese, Pisa, Italy

Application June 30, 1936, Serial No. 88,225
In Italy March 31, 1936

4 Claims. (Cl. 299—119)

My present invention has for its object to provide an improved ejector head for burners, atomizers and similar nozzles, comprising a spherocylindrical member placed in a hollow seat of complementary shape, and provided with passage grooves for the liquid to be ejected. The said grooves on the cylindrical part of the said member are of helical winding which is extended onto the hemispherical part of the member up to the polar region where it becomes helico-spiral.

In the polar region of the said hemispheric member a small cylindrical recess is provided, which is coaxial with the said member, and in which a conical element is placed which is coaxial with the said member and the function of which is to direct the liquid (flowing to the said cylindrical recess and coming from the said grooves) to the coaxial bore in the said seat of the ejector head from which the liquid is discharged in the shape of an open cone of finely subdivided liquid.

The invention is illustrated by way of example in one of its modifications in the annexed drawing in which:

Fig. 1 shows an axial section of ejector head subject matter of my present invention.

Fig. 2 is a front view of the spherocylindrical member forming a part of the ejector head shown in Fig. 1, and

Figs. 3 and 4 are a side and back elevation, respectively, of the said spherocylindrical member.

In the said drawing, 1 is a nozzle head, for instance a burner, and 2 is a bore provided therein, in which the spherocylindrical member 3 is arranged. The latter is provided with helical grooves 4 on the cylindrical portion 5 which are extended with helico-spiral winding onto the hemispherical portion 6 of member 3.

Grooves 4 discharge in front into a cylindrical chamber 7 in which a conical member 8 is provided, coaxial with member 3 and having the purpose of conveying the liquid from grooves 4 to exit channel 9 of head 1, followed by the conical widening 10.

In the modification of invention shown in the drawing for purposes of illustration the conical member 8 is axially movable, being supported by a screw-threaded rod 11 screwed into the screw-threaded bore 12 of the spherocylindrical member 3 and fixed in place by a counter-screw 13. The conical member 8 may, however, be made fixed if this is desirable. The conical point or tip 8 forms with cavity 14 in the inner wall of head 1 a nozzle 15 which may be controlled, or not, by the movement of the said tip 8. This nozzle 15 is formed by the interstice between the conical surface of the generatrix AB of tip 8

and the conical surface of the generatrix AC of head 1.

My present invention has been described and illustrated by way of example in a preferred modification, but it is understood that it is liable of structural variations without departing from the scope of invention.

Conical member 8, for instance, instead of being axially movable may be fixed.

Having now particularly described and ascertained the nature of my said invention and in what manner the same is to be performed, I declare that what I claim is:

1. An atomizer comprising a body portion having an axially disposed spherocylindrical recess and an axially disposed channel communicating with said recess, a bevelled surface located in said body portion between said recess and channel, an insert of spherocylindrical shape located fixedly in said recess, said insert having an axial recess and spiral grooves on its surface terminating in said axial recess and a conical member located in said axial recess.

2. An atomizer comprising a body portion having an axially disposed spherocylindrical recess and an axially disposed channel communicating with said recess, a bevelled surface located in said body portion between said recess and channel, an insert of spherocylindrical shape located fixedly in said recess, said insert having an axial recess and spiral grooves on its surface terminating in said axial recess and an adjustable conical member located in said axial recess.

3. An atomizer comprising a body portion having an axially disposed spherocylindrical recess and an axially disposed channel communicating with said recess, a bevelled surface located in said body portion between said recess and channel, an insert of spherocylindrical shape located fixedly in said recess, said insert having an axial recess and spiral grooves on its surface terminating in said axial recess and a conical member located in said axial recess and the conical surface of said member and said bevelled surface being located in non-parallel relation.

4. An atomizer comprising a body portion having an axially disposed spherocylindrical recess and an axially disposed channel communicating with said recess, a bevelled surface located in said body portion between said recess and channel, an insert of spherocylindrical shape located fixedly in said recess, said insert having an axial recess and spiral grooves on its surface terminating in said axial recess and a conical member located in said axial recess, and the conical surface of said member and said bevelled surface being in spaced relation and converging toward the longitudinal axis of said body portion.

PIETRO DEL GENOVESE. 60
